UNITED STATES PATENT OFFICE

SAMUEL W. REECE, OF NEW YORK, N. Y.

CANDY WRAPPER

Application filed August 23, 1927. Serial No. 214,948.

This invention relates to packages for food products, and more specifically to wrappers suitable for candy piece goods.

The principal object of this invention is to provide a package wrapper for piece goods such as candy which will display the contents of the wrapper, and yet, not adhere to the goods contained therein.

It is well known in the art to use wax or glassine paper as a wrapping material for candy. These materials, however, fail to display the contents of the package to advantage. The use of cellophane and fenestra, very transparent materials, are highly desirable, but because of the inherent nature of the material, moisture is absorbed from the candy, and causes the cellophane or fenestra (depending upon which is used), to adhere to the candy, thus making a very unsatisfactory wrapper, especially in warm weather. The solution of this problem I have obtained by using wax paper or a similar paper as a major portion of the wrapper, causing sight openings to be formed in a portion of the wrapper directly over the part of the candy I wish to display and placing cellophane or fenestra over the sight opening.

Another object is to provide a package of unique construction for the vending of candy or similar articles.

With this, and other objects in view, the invention resides in the features of construction described, and the principle upon which they operate, arrangement of parts, and the combination thereof, which will hereinafter be fully described.

Referring to the drawing:—

Figure 1 is a perspective of the package;

Figure 2 is a section taken through the wrapper which is removed from the candy; and,

Figure 3 is a section taken through the package shown in Figure 1.

In the drawings, similar parts are designated by like numerals:—

Numeral 1 designates a candy package having a wrapper 2, composed of wax or glassine paper 3, and sight openings 4, a transparent material 5, such as cellophane or fenestra covering the said sight opening.

Within the wrapper is shown a piece of candy 6, having a depressed upper surface 7 on which are shown nuts and similar articles 8.

As actually used, the candy will be placed in the wrapper so that the portion of the candy to be displayed will come directly beneath the transparent material. By having a slight depression in the top of the candy, the candy will not contact with the transparent material and thus avoid the danger of the candy adhering to the wrapper. However, it has been found that even without depressing the surface of the candy, the candy will not adhere to any great extent, as the contacting surface is so small that there is very little adhesion. The display of the contents of small package goods is highly desirable and fills a long felt need in the trade.

It is evident that the type of package shown and described herein may be varied, and I do not limit myself to the specific type shown herewith; and allow myself the privilege of applying my invention to the various types of articles which may fall within the scope of my invention.

Although I have specifically described my invention as used in connection with a candy package, I do not limit myself to such use; as the wrapper may be used in connection with cakes, bread, fruits, meats, and many other articles.

Having described my invention, what I claim as new and novel is:—

A candy package comprising a candy piece having a recess in one of its surfaces, a wrapper of material which does not stick readily to the candy piece, and having a sight opening coinciding with the recess formed in said candy piece, and a sheet of transparent material which does stick readily to said candy piece placed over the recess in the piece and secured to said wrapper out of contact with said candy piece.

In testimony whereof I affix my signature.

SAMUEL W. REECE.
